UNITED STATES PATENT OFFICE

2,185,638

UPPER ROUGHING MACHINE

Elzear J. Le Gault, Haverhill, Mass., assignor, by direct and mesne assignments, to Bestoe Shoe Machinery Inc., Ipswich, Mass., a corporation of Massachusetts

Application August 11, 1937, Serial No. 158,483

3 Claims. (Cl. 69—1)

This invention relates to machines for roughing the over-lasted margins of shoe uppers to prepare them for a subsequent cementing operation. In the manufacture of cemented shoes it has been found that the cement will not form a permanent bond with the surface of the upper unless the latter is roughened to some degree. This is especially so when glazed leather is used for upper material.

10 The machines which have been used for roughing uppers have proved unsatisfactory in that many times the operator presents the shoe to the machine in such a way that the roughing roll mars that surface of the upper which has not been lasted over. In other words, when the shoe is finished, there is an exposed scar which may render it unsaleable or at least require a repairing operation.

In one aspect the present invention consists 20 in a roughing machine of compact and convenient arrangement having abrading tools or rolls of different contour adapted for operating upon different parts of a lasted shoe bottom, for example the concave shank and the flat forepart, and being so arranged that the operator may present the shoe conveniently and practically in a continuous motion from one roll to the other. The roughing machine of my invention has therefore the capacity for a high rate of production 30 and the abrading operation may be carried out upon different parts of the shoe bottom accurately in the desired size and without liability of damaging the shoe.

This invention envisages an adjustable work gauge to be mounted in front of a forepart roughing roll, and an important feature of the invention consists in an apertured plate through which an arc of the roughing roll protrudes, the length 40 of the arc being determined by the position of the work gauge.

Another object of the invention is to prevent injuries by placing the work gauge between the operator and the roughing roll so that it may 45 serve the function of a guard, with the result that the greater portion of the roughing roll is covered.

A further feature of the invention consists in a housing having hinged plates on either end of 50 the machine so that access to the roughing rolls may easily be had.

These and other features and advantages of the invention will be more easily understood from the following description of a preferred embodiment thereof, selected for purposes of illustra-

tion and shown in the accompanying drawing, in which:

Fig. 1 is a view in front elevation of the machine;

Fig. 2 is a view in cross-section taken along line 2—2 of Fig. 1; and

Fig. 3 is a view in cross-section taken along line 3—3 of Fig. 1.

Bolted to a suitable base 10 is a casting 11 which carries bearings for a horizontal shaft 12. The shaft 12 is driven by a belt connecting the pulley 13 to any suitable source of power.

A small roll 14 is keyed on the shaft 12 at one of its ends. This roll 14 is provided with a radial wire brush 15 and is adapted by the convex contour of its surface for roughing the over-lasted margin of the upper in the concave shank portions of the shoe. Also bolted to the base 10 is a dust shield or hood 16 having a connection to a suction duct 17. The dust shield 16 substantially surrounds the roughing roll 14.

In order that access to the roughing roll 14 may be had, a plate 18 is provided in the side of the dust hood 16, hinged at 19 and secured at the top by a thumbscrew 20. At the opposite 25 end of the shaft 12 a forepart roughing roll 21 is carried. This forepart roughing roll 21 is similar to the shank roughing roll 14, although it is larger in every dimension and has a relatively wide, flat peripheral surface. Surrounding the 30 forepart roughing roll 21 is a second dust hood 22 which is connected to suction duct 23.

A gauge plate 24, shown as having a centrally located substantially square aperture is mounted in front of the forepart roughing roll 21. Horizontal rods 25 and 26 extend at right angles to the plate 24. These rods 25 and 26 pass into holes in bosses upon the sides of the dust hood 22 and may be adjustably secured in place by thumb screws 27. The two rods 25 are mounted 40 near the bottom of the plate 24, the rod 26 being located at the top.

The central aperture in the gauge plate 24 is arranged to admit a portion of the periphery of the roughing roll 21, and by loosening the 45 thumb screws 27 it is possible to move the plate 24 in and out until the desired portion of the roughing roll 21 extends through the aperture.

The outer end of the dust hood 22 is provided with a plate 28 hinged at 29 and provided with a retaining spring clip 30. By releasing the spring clip 30, it is possible to swing down the plate 28 and expose the end of the shaft 12 and the forepart roughing roll 21 for purposes of 50 replacement or repair.

5 The plate 24 offers a flat gauging surface against which the operator can place the bottom of the forepart of the shoe. By bringing the flat bottom of the shoe into engagement with the flat face of the plate 24 and then moving the shoe while held in this relation, the operation of the abrading roll 21 is defined and limited to the flat areas of the over-lasted margin, to the exclusion of the side walls of the upper. 10 Furthermore, the plate 24 prevents the operator from thrusting his hands into engagement with the wheel 21 and thus receiving injuries.

15 It is important to note that by controlling the size of the segment of the roll 21 which protrudes through the gauge plate 24 a greater or lesser degree of roughing can be obtained. On relatively delicate upper material it is desirable not to subject the leather to harsh treatment, and, by permitting only short lengths of the wire brush to protrude, the roughing is more delicate 20 and the leather is not seriously weakened.

25 Those skilled in the art will immediately perceive many possible changes and adaptations in the invention as shown and described, but such variations are incorporated in the scope of the invention and do not depart therefrom.

Having thus described my invention what I claim as new and desire to secure by Letters Patent of the United States is,

30 1. In a roughing machine comprising a fore-part roughing roll and a dust hood surrounding

said wheel, apertured lugs disposed on said dust hood, an adjustable gauge consisting of a centrally apertured plate, adjusting rods carried on said plate, said rods being dimensioned to enter the apertures in said lugs, and thumb screws disposed on said dust hood for clamping said adjusting rods in position. 5

2. In a roughing machine comprising a fore-part roughing wheel and a dust hood surrounding said wheel, an adjustable gauge consisting of a rectangular plate having a centrally located, rectangular aperture, supporting and adjusting rods carried by said plate, means carried on said hood for receiving the rods, and thumb screws disposed on said hood and cooperating with said means to secure said rods, movement of said plate permitting a greater or lesser portion of said roughing roll to be exposed through said aperture. 10

3. An upper roughing machine comprising a 20 shaft, a roughing roll carried on said shaft, a dust hood surrounding said roughing roll and having apertured lugs secured thereto, a centrally apertured gauge plate, a plurality of supporting and adjusting rods projecting rearwardly from said gauge plate, and means for clamping said rods in said apertured lugs whereby said gauge plate is adjustably held before said roughing roll. 25
